(57) **CLAIM**

The ornamental design for a travel mug, as shown and described.

DESCRIPTION

FIG. 1 is a perspective view of a travel mug, showing our new design in a first embodiment;

FIG. 2 is a front view of the embodiment shown in FIG. 1;
FIG. 3 is a back view of the embodiment shown in FIG. 1;
FIG. 4 is a side view of the embodiment shown in FIG. 1;
FIG. 5 is another side view of the embodiment shown in FIG. 1;

FIG. 6 is a top view of the embodiment shown in FIG. 1;
FIG. 7 is a bottom view of the embodiment shown in FIG. 1;

FIG. 8 is a rear perspective view of the embodiment shown in FIG. 1;

FIG. 9 is a perspective view of a travel mug, showing our new design in another embodiment;

FIG. 10 is a front view of the embodiment shown in FIG. 9;
FIG. 11 is a back view of the embodiment shown in FIG. 9;
FIG. 12 is a side view of the embodiment shown in FIG. 9;
FIG. 13 is another side view of the embodiment shown in FIG. 9;

FIG. 14 is a top view of the embodiment shown in FIG. 9;
FIG. 15 is a bottom view of the embodiment shown in FIG. 9; and,

FIG. 16 is a rear perspective view of the embodiment shown in FIG. 9.

The broken lines in the figures are for environmental purposes only and form no part of the claimed design.

The oblique line shading shown in the embodiments of FIGS. 9-16 represents a metallic surface such as stainless steel.
